UNITED STATES PATENT OFFICE.

JESSE POWERS, OF CHICAGO, ILLINOIS.

IRONING-MACHINE.

SPECIFICATION forming part of Letters Patent No. 275,851, dated April 17, 1883.

Application filed March 7, 1881. Renewed February 28, 1883. (No model.)

To all whom it may concern:

Be it known that I, JESSE POWERS, of Chicago, in the county of Cook and State of Illinois, have invented certain new and useful 5 Improvements in an Ironing-Machine; and I do hereby declare the following to be a full, clear, and exact description of the invention, that will enable others skilled in the art to which it appertains to construct and use the 10 same, reference being had to the accompanying drawings, and to letters of reference marked thereon, forming a part of this specification.

This invention relates to that class of ironing-machines which are intended to be operated by hand-power; and it consists in an ironing-machine having a polishing-roller carried over the bed by a swinging frame operated by a foot elbow-lever, cord, and hand-lever, whereof the exact construction, arrangement, 20 and operation will be hereinafter more fully set forth and described in detail.

Figure 1 is a side elevation of an ironing-machine embodying my improvements; Fig. 2, a view looking from above, with the upper 25 part removed, in the plane 2 2, Fig. 1; Fig. 3, a detached detail of construction.

Referring to the drawings, A represents the supporting frame-work; A', the ironing-bed, having a convex surface both longitudinally 30 and transversely. This ironing-bed is convex longitudinally in order to have the required radius for the traveling end of the frame carrying the ironing-roller, and convex transversely in order to present a corresponding 35 surface to the concave ironing-roller, and also to properly iron a shirt and impart to it the required shape.

The concave ironing-roller A² is suspended between the upper ends of the bars A³, which 40 embrace both sides of the frame-work and are connected together at the top by the cross-bar a. The lower ends of these bars have pivotal bearings on shaft A⁴, which is attached to and supported by the foot-lever B. The upper 45 ends of said side bars carry the ironing-roller and travel the length of the ironing-bed. The foot-lever B is pivoted to the frame at b, and therefore, when pressed downward, the bar A⁴ and the side bars are drawn downward also 50 and give a heavy pressure of the roller on the ironing-bed. Generally this lever will be of

such a weight as to automatically impart a sufficient pressure to the ironing mechanism for all ordinary purposes.

Attached to the shaft B' is the eccentric 55 hand-lever B², which has a connection with the foot-lever B by means of the cord B³. This hand-lever B² is for the purpose of quickly and easily raising the lever B, and thereby raising the ironing-roller up from contact with the bed. 60 This arrangement is rendered necessary from the fact that the foot-lever B is very heavy and not easily moved in an upward direction. Therefore when the ironing-roller becomes too hot the operator is enabled, through the medium 65 of the eccentric hand-lever B², to easily elevate the roller above the bed.

When the ironing-roller is run off from the end of the bed, as shown by the dotted lines in Fig. 1 of the drawings, the lower portion of 70 the swinging frame comes in contact with the vertical extension B⁴ of the foot-lever B, and by this arrangement the weight of the horizontal part of the foot-lever greatly assists in returning the roller to the ironing-bed. By 75 removing the roller from the bed a skirt or dress may be drawn on over the end of the bed, which is made to project considerably beyond the supporting-frame for this purpose.

The ironing-roller is operated by means of the 80 hand-crank C, and travels over the ironing-bed by mere frictional contact with the same. The roller being of the form described—that is, considerably less in diameter in the middle than at the extreme polishing ends—serves to 85 impart something of a sliding action to the middle of the roller, which comes in contact with that part of the shirt-bosom where the nicest polish is required.

Another particular feature of this apparatus is, that, being operated by hand, the operator is enabled to stop the roller at any point on the ironing-bed, and by imparting a reciprocating action a very high polish may be given to any one particular part of the garment. 95 This feature is a very important one in an apparatus that is more especially intended as a shirt-ironer, as the reciprocating motion will impart a fine polish to the bosom.

The ironing-roller is hollow, and may be 100 heated with steam, gas, or "slugs," as may be convenient.

This apparatus constructed with the supporting-frame is more especially designed for use in laundries.

Having thus described my invention, what I claim, and desire to secure by Letters Patent, is—

In an ironing-machine, the combination, with the polishing-roller A², of the swinging frame

A³, the foot-lever B, with its elbow B⁴, the cord B³, and the hand-lever B², substantially as described, and for the purpose set forth.

JESSE POWERS.
